UNITED STATES PATENT OFFICE

JOHN H. LARGE, OF CALDWELL, NEW JERSEY, ASSIGNOR TO INTERNATIONAL MUSICAL CORPORATION, OF HOBOKEN, NEW JERSEY, A CORPORATION OF NEW JERSEY

DESIGN FOR A ZITHER OR SIMILAR ARTICLE

Application filed April 23, 1928. Serial No. 26,432. Term of patent 14 years.

To all whom it may concern:

Be it known that I, JOHN H. LARGE, a citizen of the United States, residing at Caldwell, in the county of Essex and State of New Jersey, have invented a new, original, and ornamental Design for a Zither or Similar Article, of which the following is a specification, reference being had to the drawing, forming a part thereof, of which—

I claim:

The ornamental design for a zither or similar article, as shown.

JOHN H. LARGE.
